UNITED STATES PATENT OFFICE.

HERMAN HODGSON AND GERALD F. REYNOLDS, OF CORTLAND, NEW YORK, ASSIGNEES
TO CORTLAND LINE CO., INC., OF CORTLAND, NEW YORK, A CORPORATION OF
NEW YORK.

KNOCK-OFF DEVICE FOR BRAIDING MACHINES.

Application filed December 26, 1924. Serial No. 758,183.

To all whom it may concern:

Be it known that we, HERMAN HODGSON and GERALD F. REYNOLDS, citizens of the United States, and residents of Cortland, 5 in the county of Cortland and the State of New York, have invented certain new and useful Improvements in Knock-Off Devices for Braiding Machines, of which the following is a specification.

Our invention relates to improvements in the art of braiding machinery, and its primary object is to provide for a simple and novel knock-off device for machines of this character that will serve immediately to 10 shut down the operation thereof in the event any one of the yarn strands in either the core or its surrounding braid should accidentally or otherwise become ruptured during the weaving process. Our invention is 15 further directed toward improved facilities for evenly tensioning multiple-ply core strands for such braids, especially as applied to the making of fish lines, candle wicks, bead cords, racket cords, shoe strings, lamp 20 cords, airplane cords, parachute drop cords, sash cords, and other cords of the braided type that are provided with core strands 25 made of yarn, wire, rubber, or the like.

In the manufacture of such lines or cords, 30 a plaited braid is commonly woven about either a single or multiple ply core strand by interlacing alternate braid strands over and under each other to form a closely woven tubular braid adapted to surround 35 said core strand or strands. The conventional braiding machine accomplishes this purpose by the use of a series of intermeshed gear-driven bobbin carriers which are power-driven and adapted to travel in a circuitous 40 path about the axle of the centrally disposed core strands in such a fashion that the yarn bobbin carriers may pass each other while effecting the indicated plaiting of the braid.

Each yarn bobbin on such rotating braider 45 strand carriers or spindles may be provided with a suspended ratchet feed weight of the conventional type adapted to maintain a substantially uniform tension upon all of the braid strands while these are being unwound 50 from their respective yarn bobbins. The drive shaft of our braider machine is preferable equipped with a disengageable clutch of such construction that should any one of the

braid strands become accidentally ruptured during the weaving operation, then the tensioning weight normally suspended by the defective strand is allowed to drop to a lower position on its travelling bobbin carrier, which in turn is made to shift a knock-off arm and to trip a latch for the release of a suitable stop mechanism. The drive shaft clutch is thereby thrown out of engagement and this promptly brings the machine to rest, thus effectively preventing the further making of any defective braid around the core. 55 60 65

Heretofore this desirable stop feature has been applied to the breakage of braider strands alone. An outstanding feature of the present invention lies in an extension of the stop feature for braiding machinery, so 70 as to effect a similar result as applied to the core strands and thus provide for a full stop device adapted to respond not only to the breakage of the braider strands but to the core strands as well. 75

Our improved braider machine further contemplates keeping the multiple core strands evenly tensioned with respect to the braider strands during the braiding process and to bring a common stop mechanism into 80 action immediately upon an accidental rupture of any of such plaited core strands. In the making of uniform high grade cored braids it is found of utmost importance to keep all the core and also the braider strands 85 evenly and automatically tensioned, and this requirement is one that has not heretofore been adequately met. Furthermore, as previously constructed, braiding machines are apt to continue braiding about one or more severed core strands until such time that a defect of this kind may come to the operator's notice. Since it is customary to let one operator attend a considerable number 90 of such machines, our improved automatic 95 means for shutting down operation immediately upon the breaking asunder of any one of the core strands greatly facilitates 100 and extends the supervision of such one-man operation as compared to the present type of equipment. Defective cords for the braid are thereby obviated and the cost of labor and waste of material are reduced to a minimum besides providing for a more uniform 105 and consistent quality in such braided products.

Embodying herein are also other features of structure and organization adapted to facilitate the manufacture of encased braided cords or lines, all of which will be set forth in detail hereinafter.

Reference is had to the accompanying two sheets of drawings which illustrate an example of our invention, in which drawings like characters of reference indicate like parts in the several views, and in which drawings:

Fig. 1 represents a perspective view of a small braiding machine equiped with our improved device as applied to the making of lines or cords having but a single-ply strand for their core.

Fig. 2 is a top or plan view of the braider machine as taken along line 2—2 of Fig. 1.

Fig. 3 is a partial sectional view illustrating the constructive details of an assembled bobbin carrier and appurtenances, particularly a unit such as may be used for core strand purposes but except for a minor modification, this unit is also applicable to 25 braider strands as used in connection with the machine shown in Fig. 1.

Fig. 3^a represents a top view of the carrier shown in Fig. 3.

Fig. 4 is an enlarged partial view of the 30 braider machine detailing the detachable clutch mechanism as seen from line 4—4 of Fig. 2.

Fig. 5 shows further details of the knock-off or stop devices that co-operate with the 35 drive clutch and the rotating bobbin carriers as taken along line 5—5 of Fig. 4.

Fig. 6 is a plan view of our knock-off plate for mounting our core strand carriers, which plate may readily be attached to certain existing braider machines to equip them with our improved core knock-off devices.

Fig. 7 represents a plan view similar to Fig. 2, but indicating a modified braider machine equiped with plural bobbin carriers 45 adapted to make a three-ply strand core for the braid.

Referring first to Figs. 1 and 2, the letter A₁ represents a stationary top plate or platen of our braider machine, which platen may be provided with a set of complementary 50 cut-through grooves A₂ and A₃ respectively, forming oppositely disposed and intersecting sinuous paths disposed about the center of the platen. These grooves are preferably formed by means of a plurality of tangentially disposed or abutting circular component grooves which connect with each other to constitute an endless serpentine-like crossed groove as shown. It will be observed 55 that in this particular disclosure, the two circular end or return elements of said closed grooves are spaced somewhat apart and to this extent are not made entirely symmetrical with respect to the axis of the round platen.

The center portion of such circular component is provided with a platen stud member A₄ which extends downward and is attached to the bottom plate A₅ in order to support the inset center member or quoit A₆ 70 in alignment with the platen surface as shown. Between the spaced bottom plate A₅ and the said top plate A₁, a series of intermeshing horn gears such as A₇ are rotatably mounted on the respective studs such as A₄, 75 and these gears are each provided with suitable lugs or horns in the conventional manner, as indicated by A₈.

A series of bobbin carriers as used for the braider strands are mounted to ride upon 80 the top platen face of which only one such carrier unit is represented in Fig. 1 and designated as B₁.

In the present instance, ten such units are preferably used in connection with the described endless platen grooves 85 designated as A₂ and A₃, and the disposition of said units is indicated in Fig. 2 by dotted circular lines. Each such braider carrier is preferably provided with an oblong or oval-shaped bobbin shoe B₂ of conventional construction adapted to slide freely in said platen groove while the projecting shoe tip B₃ is intended to successively engage the various gear lugs or horns A₈ in such manner as will cause the different carriers to travel in 95 spaced relation around the closed sinuous platen groove. The disposition of the horn actuating elements A₈ for such carriers is such that the carriers are made to pass each other along the double separated portion of 100 said grooves as indicated in Fig. 2, to the end that one-half of the plural carriers first travel around one of the sinuous grooves in a clockwise direction while the other half of the carriers travel in the complementary 105 groove in the opposite direction, all in accordance with conventional braiding machine practice.

Since the means for imparting movement to the respective carriers do not constitute the essential subject matter of our improvements, it is sufficient for present purposes to outline suitable means whereby the various carriers are commonly kept in movement about the platen axis for the purpose of effecting the braiding process about the centrally disposed core strands. The core bobbin carriers remain stationary except as they gradually feed their strand up through the center of the platen as indicated in Fig. 1 by dotted and dashed lines D₄. 115

Referring now to the drive mechanism used for rotating the enmeshed platen gears, such as A₇, these are side driven as a unit by the intermediate spur gear A₉, which is mounted and preferably keyed to the power 120 driven upright auxiliary shaft C₁. A releasable clutch is provided for starting and stopping the operation of the braider machine and any suitable drive-disengaging device will serve present purposes. In the ex- 125

ample, illustrated in Figs. 4 and 5, the slip bevel gear C_5 may be provided with an extended hub portion C_4 having a clutch socket C_2 and this is detachably engaged by the 5 clutch lug C_3 as shown in Fig. 5. The slip gear may be held up in place by a collar or other suitable means and is intended to rotate freely with respect to the auxiliary shaft C_1 and without rotating the spur gear A_9 , whenever 10 the lug C_3 is withdrawn from the socket C_2 . Mounted upon the lower end of such auxiliary shaft C_1 is a clutch plate C_6 which is provided with a grooved slip collar that engages but is intended to rotate freely with 15 respect to the fork end pin C_7 of the fulcrumed clutch lever C_8 . This lever is overhung and when released is adapted to drop freely so that its own unbalanced weight will automatically pull the clutch pin out of 20 engagement with its socket C_2 . The slip gear C_5 meshes with the complementary bevel gear C_9 , which latter gear may be suitably fastened and centered upon the drive pulley C_{10} . Both of the last-named parts 25 are mounted on the horizontal layshaft C_{11} , which in turn is overhung from a convenient portion of the machine frame such as C_{12} .

The outer portion of the clutch lever C_8 is further provided with a trip or latch link 30 C_{13} fulcrumed at its lower extremity to said lever and extending upwards through the latch guide C_{14} . The upper portion of the link C_{13} is equipt with a latch C'_{13} and when the lever C_8 is raised into its full-lined position, this projecting latch edge is intended 35 to engage the guide plate C_{14} as shown in Fig. 1 and hold the clutch in its operative position. The extreme end of the link C_{13} is further provided with a projecting lug 40 portion C_{18} adapted to overhang the knock-off arm C_{15} so as to prevent the lever C_8 from falling below the dotted position (Fig. 5) when the clutch is disengaged.

The knock-off arm C_{15} preferably comprises a flat arcuate plate of which one end is freely fulcrumed at C_{16} to the top face of the platen A_1 . As shown in Fig. 1, the other end of said drum is provided with a knob portion C_{17} which lies close to but is 50 still made to normally clear the path travelling parts associated with any of the movable braider carriers such as B_1 . Since the upper or free end of the pivoted link C_{13} rests alongside the outer circular edge of 55 the arm C_{15} , it will be apparent that any outward movement imparted to this fulcrumed arm will serve to trip the latch C'_{13} and thus cause the clutch to be thrown out of engagement.

60 The disposition of the various parts is such that should for any reason, the yarn strands on any one of the travelling bobbin carriers become ruptured, it will allow a suitable drop weight previously suspended 65 by said strand to fall and thereupon come

into engagement with the knock-off knob portion C_{17} and cause this to be shifted outwards and away from such carrier whose yarn strand may have become ruptured. As a result the clutch pin C_3 will be thrown out 70 of engagement and this in turn shuts down the further operation of the braider machine, although the released drive pulley C_{10} may continue to rotate freely upon the lay shaft C_{11} . As applied to the braider strands, the mechanism required is substantially similar to that being conventionally used for this purpose, and is merely set forth in sufficient detail to permit the disposition and importance of our improved attachment 75 to be readily and fully understood. As stated, the yarn spool of the plural bobbin carriers is made to travel around the endless platen groove, and as is further detailed in Fig. 3, each of these carriers substantially 80 comprises a vertical spindle B_4 on which a bobbin or spool B_5 is loosely mounted and adapted to gradually feed off evenly tensioned yarn to the respective braid strands. The uppermost flange of each bobbin is provided 85 with a series of upstanding ratchet teeth such as B_6 , which successively engage with a suitable bobbin pawl B_7 , serving to tension and regulate the unwinding of the yarn off the bobbin. Mounted alongside the 90 bobbin axis is an offset weight rod B_8 , the lower end of which is firmly secured to and projects upward from the shoe or foot portion of the housing, while the upper end of 95 said rod is equipt with a rod eye B_9 .

Slidably mounted upon each such rod are two separate weights of which the upper or pawl weight B_{10} is provided with said overhung bobbin pawl B_7 adapted to engage the 100 ratchet teeth B_6 and ride thereon, while the lower or drop weight B_{11} is equipt with a 105 yarn eye B_{12} . The yarn feeding off the bobbin is threaded first through the eye B_{12} and then under the outer edge of the drop weight B_{11} and through the rod eye B_9 from 110 which it passes upwards to constitute one of the braid strands. The braiding operation is performed at the apertured former B_{13} located directly above the center of the platen A_1 as shown in Fig. 1, from which 115 the various braid strands are intended to radiate to the rod eyes of the respective carriers. The length of the yarn coming from the bobbin is kept sufficiently short and taut so as to hold the lower drop weight B_{11} suspended above the platen within predetermined limits. The intended relation of the 120 yarn length is such that when the pawl B_7 of the upper weight B_{10} has just dropped behind and into the bottom of one of its co-acting ratchet teeth B_6 , the drop weight B_{11} will at that time be lowered but only to about the extent indicated by its full lined position shown in Fig. 3, in which position 125 the carrier is still allowed to travel around 130

one of the platen grooves without any interference with the projecting knob portion C_{17} of the arm C_{15} .

From the foregoing it will be seen that 5 while the braid is being formed, a substantially continuous pull will be exerted upon the receptive unruptured braid strands and this will in turn gradually lift the drop weight B_{11} since for the time being, the bobbin 10 is held and prevented from rotating by the interlocked bobbin ratchet. As soon, however, as sufficient yarn has been fed into the braid and the lower weight B_{11} has been raised to a point where it engages the pawl 15 weight B_{10} , and further feeding of the yarn into the braid will serve to raise the pawl B_7 out of locking engagement with the bobbin teeth B_6 and this action allows the bobbin to intermittently rotate into the next tooth 20 notch. In the meantime, the drop weight B_{11} is again allowed to fall into said full lined position with the result that this intermittent feed method serves to keep a substantially constant tension on the different braid strands and all substantially 25 equal to each other.

The continuously formed braid will be automatically wound up on the reel B_{14} in the usual manner by adjustable gear devices 30 such as are indicated in Fig. 1. As stated, all of the carriers are intended to be similarly equipped with the described ratchet tensioning device, and in the event that any one of the braid strands should rupture, 35 this will allow the corresponding drop weight B_{11} to fall below its normal suspended position and into extreme lower position indicated by dotted lines in Fig. 3. Thereupon an interference will be set up 40 between the drop weight mounted upon the travelling carrier rod B_8 and the pivotally mounted knock-off arm C_{15} of which the knob portion C_{17} is disposed to project into the path of the drop weight whenever any 45 one of such drop weights is allowed to reach said dotted position. Such striking of the arm C_{15} by the drop weight B_{11} causes a slight rotation about its fulcrum C_{16} , which in turn serves to trip the latch link and allows the clutch lever C_8 to drop somewhat 50 and disengage the power driven mechanism in the manner described and thus cause the braiding operation to immediately cease.

It may here be pointed out that as used 55 in connection with our braiding machine, the bobbin carrier shown in Fig. 3 is applicable to both braider strand or core strand purposes except for a minor change in the foot housing constructive details. In the case of 60 the braider strand carrier its foot housing is intended to be provided with an oval or oblong shoe such as B_2 , which as indicated in Fig. 1 is slidably mounted to travel around the platen groove in the conventional manner. When applied to core 65

strand purposes, it is preferred to modify the braider carrier structure somewhat into the precise form detailed in Fig. 3. In this structure, the bottom of the housing B_{17} is equipped with a shallow foot lug B_{15} which has 70 an elongated shape as indicated by dotted lines in Fig. 3*, and provided with a stud member B_{16} having a suitable nut serving as a clamping member, as will appear presently. 75

Referring now more specifically to our particular improvements in the type of braiding machine heretofore described it is pointed out that provision is made to apply similar stop safety devices to the core 80 strands about which the braid is formed. In the conventional braider machine, the core strand or strands are usually fed off their respective spools from below the platen through a central hole without adequate 85 tensioning means and thence pass up to the former B_{13} , when the core is braided in the manner previously set forth. It is found however that with the conventional equipment heretofore used, serious difficulty is 90 generally experienced in keeping the core 95 strands evenly and properly tensioned, particularly so when plural core strands are employed. It is the purpose of the present invention to remedy this defect 100 and to provide suitable means which will also cause the knock-off arm C_{15} to be actuated by any rupture on part of the core strands in a manner analogous to that which was described in connection 105 with the braider strands. When each of the core strands are suitably equipped with the describing ratchet bobbin carrier and appurtenance, our machine provides for a full stop device throughout all the yarn 110 strands that go to make up any braided cord or line. 115

An essential requirement for this purpose is the provision of a moving element for the core strand carrier capable of actuating the knock-off arm C_{15} or its equivalent, in the event any one of the core strands should become ruptured. Without such moving element such as the cam D_5 , the drop weight such as B_{11} applied to the core bobbin, would not effect the desired results, for the reason that this particular bobbin carrier remains stationary in the sense that it is not kept in translatory motion as are the braider 120 bobbin carriers. In the embodiment of our invention, as applied to conventional braid- 125 ers, we prefer to provide for an attached knock-off plate D_1 , such as for example is shown in Fig. 6, which may readily be attached to certain existing machines of the braider type. This plate may be provided with screw receiving holes D_2 and also with one or more relatively long radially disposed slots such as D_3 ; any one of which slots is intended to receive and engage the 130

elongated foot lug B_{15} of the core strand carrier. The slot length is preferably made longer than the major axis of said lug since this not only prevents rotation of the carrier but also allows of adjustably mounting same with respect to the plate D_1 . The nut on the stud B_{16} serves to adjustably clamp the carrier lengthwise of the knock-off plate slot.

10 The holes D_2 may be used to secure the plate D_1 to the pivoted knock-off arm C_{15} so as to virtually become an integral part thereof. The elongated slot D_3 allows of shifting the carrier into any desired relation with respect to the actuating eccentric D_5 , whose function will be more fully set forth presently. The preferred position of the attached knock-off plate D_1 in relation to the pivoted knock-off arm C_{15} is shown in 15 Figs. 1 and 2, and for clearness of illustration, only a one-core bobbin carrier is mounted in place to constitute a single-ply core braiding machine, although it will be understood that for multiple cores, a plurality of similar core bobbins may be carried by the plate D_1 , if so desired. The core yarn D_4 feeding off the ratcheted bobbin carrier B_6 may be run over suitable pulleys so as to come up centrally through 20 the platen A_1 as indicated by dotted and dashed lines in Fig. 1. It will be understood that instead of employing a bobbin B_5 for the carrier such as is shown in Fig. 3, it may be preferred, especially in the case 25 of having to deal with a relatively heavy core strand or center, to utilize a cone shaped spool on the bobbin spindle in which event one or more turns are merely wrapped about said special spool, which then feeds 30 the core into the braid in the customary manner.

For the purpose of imparting the required movement for disengaging the clutch mechanism in the event that any of the 45 core strands should become ruptured, the rotating auxiliary shaft C_1 is preferably provided with an eccentric or cam D_5 or similar actuating element as indicated in Fig. 1. From the previous description of 50 the conventional braider machine, it will be apparent that the auxiliary shaft C_1 is kept in rotation while the clutch remains engaged with the drive pulley C_{10} . The disposition 55 of the single core bobbin carrier designated as D_6 in Figs. 1 and 2, is such that in the event of the breaking of its core strands, this will allow its suspended drop weight such as B_{11} to fall into the extreme bottom 60 position corresponding to that shown dotted in Fig. 3. The shape and disposition of this drop weight is intended to be such that when it falls into its lower position, an interference will be set up with respect to the movement of the rotating eccentric D_5 , and this in turn is made to push the pivotably

mounted carrier D_6 away (see Figs. 1 and 2) from the shaft C_1 . In view of the described attachment of the knock-off plate D_1 to the pivoted knock-off arm C_{15} , it will also be apparent that the eccentric will actuate 70 said arm and thus lead to a tripping of the clutch mechanism in a manner analogous with that previously described in connection with the breakage of any one of the strands on the travelling braider carriers. Hence 75 by extremely simple means a shutdown of the machine is accomplished in the event that either the core or the braider strands should become ruptured.

As indicated in Fig. 7, a plurality of core bobbins carriers such as D_6 may be similarly disposed about the axis of the auxiliary shaft C_1 and each of these is intended to be provided with an independent drop weight such as B_{11} and adapted to co-operate with 80 the common eccentric D_5 in bringing about the described shifting of the knock-off arm C_{15} and a subsequent disengagement of the drive clutch whenever any one of the plural core strands should become ruptured. 85

In the case of Fig. 7, the type of platen groove used is modified somewhat over that previously described in connection with Figs. 1 and 2, since two independent grooves 90 are here used. In order that the respective sets of braider carriers may still actuate a common knock-off arm C_{15} , its outer free end is now given a hook shape as shown but in all other respects the operation is identical. 95

It is further pointed out that our provision for disengaging the clutch is supplemented by a regulated and an even tensioning of all the core strands by bobbin ratchet means substantially similar to that applied to the braid strands. It will be apparent therefore that our improved braider is made capable of weaving braided cords or lines of the highest grade with the minimum of material waste and labor cost, and that it meets a deficiency that has long been felt in this art. 105

It will be understood that the knock-off plate D_1 may be incorporated as an integral part of the pivoted knock-off arm C_{15} , and that we do not wish to be limited to the particular construction herein set forth, since various other changes in the details of our devices may be resorted to without departing from the spirit and scope of our invention, heretofore described and more fully set forth in the appended claims. 115

Claims:

1. In a machine for plaiting a plurality of braid strands about a core strand, said machine comprising a movable bobbin carrier with appurtenances including a suspended drop weight for each of the braider strands, a drive mechanism including a disengageable clutch, which drive is adapted to 125
2. In a machine for plaiting a plurality of braid strands about a core strand, said machine comprising a movable bobbin carrier with appurtenances including a suspended drop weight for each of the braider strands, a drive mechanism including a disengageable clutch, which drive is adapted to 130

- impart a plaiting movement to said carriers, a stop device including a knock-off arm co-operating with the said drop weights and adapted to disengage the clutch and bring 5 said carriers to rest in the event of rupture on part of any one of the said braid strands, a core strand carrier with appurtenances therefor including a drop weight normally suspended by the core strand adapted to feed 10 said core strand into the braid, and means including a cam element actuatable in unison with said drive means adapted to co-operate with the last-named drop weight and upon rupture of the core strand serving to disengage 15 said clutch in a manner analogous to that applied to the braider strands and cause further braider operations to cease.
2. In a machine for plaiting braided strands about a core strand, said machine comprising a grooved platen equipt with separate bobbin carriers slidably mounted in said groove and having a drop weight normally suspended upon each of the braider strands, a drive mechanism including a 20 releasable clutch adapted to impart a plaiting movement to such carriers, a knock-off arm adapted to interfere and be thrown out of the path of the lowered drop weight whenever rupture on part of any one of the 25 braider strands should allow its respective weight to fall below a predetermined position, a stop mechanism serving to disengage the clutch and bring said carriers to rest, said mechanism including a latch device 30 adapted to be tripped by the throwing of said arm, a core strand carrier with appurtenances including a drop weight suspended by the core strand and adapted to feed said strand into the braid, and means 35 including an actuating cam element adapted to co-operate with the last named drop weight and serving upon rupture of the core strand to throw said knock-off arm and disengage the clutch in a manner analogous to 40 that applied to the braider strands and thereby cause further braid operations to cease.
3. In a machine for plaiting braided strands about a plurality of core strands, 45 said machine comprising a movable bobbin carrier with appurtenances including a suspended drop weight for each of the braided strands, a drive mechanism including a disengageable clutch adapted to impart plaiting movement to the respective braider carriers, a stop device including a knock-off arm co-operating with said drop weights and adapted to disengage the clutch and bring 50 the carriers to rest in the event of rupture on part of any one of the braid strands, a core strand carrier with appurtenances including a suspended drop weight for each of the plural core strands, and means including a common actuating cam element adapt- 55 ed to co-operate with the last-named drop

weights serving upon rupture of any one of the said core strands to disengage said clutch in a manner analogous to that applied to the braider strands and thereby causing further braider operations to cease. 70

4. In a machine for plaiting braider strands about a core strand, said machine comprising a movable bobbin carrier with appurtenances including a suspended drop weight for each of the braider strands, a 75 drive means including a disengageable clutch adapted to impart plaiting movement to said carriers, a stop device including a knock-off arm co-operating with said drop weight and adapted to disengage the clutch and bring said carriers to rest in the event of rupture on part of any one of said braid strands, a core strand carrier with appurtenances therefor including a drop weight normally suspended upon the said core strand together with a ratchet feed device actuated by said drop weight serving to evenly tension and feed said core strand into the braid, and means including an actuating cam element adapted to cooperate with the last-named drop weight serving upon rupture of the core strand to disengage said clutch and thereby cause further braider operation to cease. 80

5. In a machine for plaiting braider strands about a plurality of core strands, said machine comprising a plurality of movable bobbin carriers with appurtenances including a drop weight normally suspended upon each of the braider strands and a 95 ratchet tensioning means adapted to maintain a substantially even tension upon each of the respective braider strands, drive means including a disengageable clutch adapted to impart plaiting movement to said carriers, a plurality of core strand carriers each similarly equipt with a ratchet and a co-operating drop weight tensioning means adapted to maintain an even tension upon the respective core strands substantially equal to that of the braider strands while said core strands are being fed into the braid, and means including a cam element actuatable in unison with said drive means serving to trip said clutch and bring 100 said carriers to rest in the event of rupture on part of any one of the core strands. 110

6. In a machine for plaiting braider strands about a core strand, said machine comprising bobbin carriers for each of the 115 braider strands, drive means adapted to impart plaiting movement to said carriers, disengaging means for said drive means serving to bring said carriers to rest, a core strand carrier including a drop weight normally suspended upon the core strand and adapted to feed a core strand into said braided strands, and a rotating actuating element operatively connected with said drive means, which element upon failure of 120

125

130

the core strand is adapted to co-operate with the lowered drop weight to disengage the drive means and bring about a cessation in the braider operations.

- 5 7. In a machine for plaiting braider strands about a plurality of core strands, said machine comprising a plurality of movable bobbin carriers with appurtenances including a drop weight normally suspended upon each of the braider strands and a ratchet tensioning means adapted to maintain a substantially even tension upon each of the respective braider strands, drive means including a disengageable clutch 10 adapted to impart plaiting movement to said carriers, a plurality of core strand carriers each similarly equipt with a ratchet and a co-operating drop weight tensioning means adapted to maintain an even tension 15 upon the respective core strands substantially equal to that of the braider strands while said core strands are being fed into the braid, and means including a cam element actuatable in unison with said drive 20 means serving to trip said clutch and bring said carriers to rest in the event of rupture on part of any one of the core strands.
8. In a machine for plaiting braid strands about a plurality of core strands, 25 said machine comprising a movable bobbin carrier including a drop weight normally suspended upon each of the braider strands adapted to maintain a substantially even tension upon each of the respective braider 30 strands, a drive means including a disengageable clutch adapted to impart plaiting movement to said carriers, a stop mechanism including a knock-off arm co-operating with said drop weights and adapted to 35 disengage the clutch and bring the carriers to rest in the event of rupture on part of any one of the braid strands, in combination with a plurality of core strand carriers also equipt with normally suspended drop 40 weights adapted to maintain a substantially even tension upon each of the respective core strands, and means including an actuating element adapted to co-operate with the last-named drop weights and serving 45 upon rupture of any one of the core strands to similarly bring about a disengagement of the clutch and thereby cause further braider operation to cease.
9. In a machine for plaiting braid strands 50 about a core strand, said machine comprising a movable bobbin carrier and appurtenances therefor adapted to serve said braider strands, a drive mechanism for imparting a plaiting movement to said carriers, a disengaging means including a clutch for said drive mechanism, a stop device including a knock-off arm adapted to trip said clutch and bring said carriers to rest, an actuating element in operative connection with said drive means, a slotted knock-off plate for 55 said knock-off arm, a core strand carrier equipt with a suspended drop weight adapted to co-operate with the actuating element and serving upon rupture of the core strand to bring about a disengagement of the 60 clutch, a foot lug for the last-named carrier adapted to engage said slotted knock-off plate and adjustably mount said carrier with respect to the actuating element, and means for locking said carrier in its adjusted position upon said knock-off plate.
10. In a machine for plaiting braider strands about a plurality of core strands, said machine comprising a movable bobbin carrier with appurtenances for each of the 65 braider strands, a drive mechanism for said carriers, a disengaging means including a clutch for said drive means, a stop device including a knock-off arm adapted to trip said clutch and bring the braider carriers 70 to rest, a rotating actuating element, a slotted knock-off plate for said knock-off arm, said plate having a plurality of slots radially disposed with respect to the actuating element, core strand carriers each equipt 75 with a suspended drop weight adapted to co-operate with the common actuating element and serving upon rupture of any one of the core strands to bring about a tripping of the clutch, a foot lug for each of the 80 last-named carriers adapted to engage its respective radial slot and serving to adjustably mount said carriers with respect to said actuating element, and means for locking said carriers in their respective adjusted 85 position upon said knock-off plate.

In testimony whereof, we have signed our names to this specification in the presence of two subscribing witnesses December, 1924.

HERMAN HODGSON.
GERALD F. REYNOLDS.

Certificate of Correction.

It is hereby certified that in Letters Patent No. 1,537,445, granted May 12, 1925, upon the application of Herman Hodgson and Gerald F. Reynolds, of Cortland, New York, for an improvement in "Knock-Off Devices for Braiding Machines," errors appear in the printed specification requiring correction as follows: Page 4, line 15, after "weight B_{10} " for the word "and" read *any*; line 103, for the word "describing" read *described*, and line 104, for the word "appurtenance" read *appurtenances*; page 6, strike out lines 95 to 117, comprising claim 5, and insert instead as claim 5:

5. In a machine for plaiting braid strands about a core strand; said machine comprising a bobbin carrier for each of the braider strands, drive means adapted to impart plaiting movement to said carriers, means serving to disengage said drive and bring the carriers to rest, a core strand carrier with appurtenances including a drop weight normally suspended upon said core strand and a ratchet tensioning means adapted to be intermittently released by said drop weight and maintain a substantially even tension on said core strand, and a cam element actuated in unison with said drive means, which element upon failure of the strand suspension is adapted to co-operate with the lowered drop weight to disengage the drive means and bring about a cessation in the braider operations.;
and that the said Letters Patent should be read with these corrections therein that the same may conform to the record of the case in the Patent Office.

Signed and sealed this 7th day of July, A. D. 1925.

[SEAL.]

WM. A. KINNAN,
Acting Commissioner of Patents.
